(57) **CLAIM**

The ornamental design for a showcase for shoe management apparatus, as shown and described.

DESCRIPTION

FIG. 1 is a front perspective view of the showcase for shoe management apparatus showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is a partial enlarged view of the area '8' as identified in FIG. 1;

FIG. 9 is a front perspective view showing the state of use that the 'C'-shaped glass part has been opened; and,

FIG. 10 is a front perspective view showing the state of use that the claimed design has been installed at the top part of the shoe management apparatus.

The broken lines depict portions of the showcase for shoe management apparatus that form no part of the claimed design. The portions of FIGS. 9 and 10 drawn in broken lines show environmental structure only and form no part of the claimed design.

1 Claim, 10 Drawing Sheets
